UNITED STATES PATENT OFFICE.

WILLIAM S. HAMM, OF HUBBARD WOODS, ILLINOIS, ASSIGNOR TO THE ADAMS & WESTLAKE COMPANY, A CORPORATION OF ILLINOIS.

AUTOMOBILE-LAMP.

1,093,618.

Specification of Letters Patent.

Patented Apr. 21, 1914.

Application filed May 2, 1912. Serial No. 694,607.

To all whom it may concern:

Be it known that I, WILLIAM S. HAMM, a citizen of the United States, and resident of Hubbard Woods, county of Cook, and State 5 of Illinois, have invented certain new and useful Improvements in Automobile-Lamps, of which the following is a specification, and which are illustrated in the accompanying drawings, forming a part thereof.

10 The invention relates to lamps especially adapted for use on automobiles; a side lamp being shown for the purpose of exemplifying it.

15 The objects of the invention are to provide an improved form of mounting the lamp, and improved means for securing access to its interior; and it consists broadly in mounting the bulb socket or burner upon a plate which may form a door for the lamp 20 body and which may be provided with a bracket-engaging socket, or may be made integral with the bracket.

25 In the accompanying drawings Figure 1 is a detail rear elevation of the lamp showing a portion of the bracket; Fig. 2 is a detail plan section on the line 2—2 of Fig. 1; Fig. 3 is a similar view showing a modified form of construction; and Fig. 4 is a detail of the supporting bracket shown in Fig. 3.

30 The body 10 of the lamp may be of any desired form and may be provided with an oil font 11. In one of the walls, as shown at the back of the body 10, there is an aperture 12, preferably circular and surrounded by a 35 frame 13 provided with hinge lugs or other suitable means of attachment. A plate 14 is fitted to the frame 13 and secured thereto by means of hinge lugs 15, 16, and pintles 17, 18, or by such other fastening devices as may 40 be preferred. As shown, either of the pintles 17, 18, may be withdrawn and either may be used as the pivot upon which the lamp body may swing.

45 In the construction illustrated in Figs. 1 and 2, the plate 14 is integral with the bracket 19 by which the lamp is supported. The bulb socket 20 may be attached to the plate 14 in any desired manner, and the wires 21, 22, for supplying the bulb with 50 current are led to the lamp through a channel formed in the bracket, as shown.

In the construction illustrated in Figs. 3 and 4, the plate 14 is provided with a loop 23 for receiving the upper end 24 of the

bracket, a binding screw 25 locking these 55 parts together. When this construction is followed the wires 21, 22, lead to terminal plates 26, 27, secured to and insulated from the end portion 24 of the bracket, and being exposed through its side face, and being so 60 disposed as to make contact with terminals 28, 29, of the socket 20, which in practice should be spring-advanced.

The inner walls of the frame 13 are preferably beveled, as shown at 30, the side edges 65 of the plate 14 being correspondingly formed, thus providing a bearing which relieves the pintles 17, 18, in a measure of the strain that would otherwise fall upon them.

Access is gained to the interior of the 70 lamp by removing one of the pintles 17, 18, and swinging the lamp body upon the other as a pivot.

While the invention is shown in connection with an incandescent bulb, other suitable illuminating devices may be used, the 75 illuminating agent being conveyed to the translating device through the bracket.

I claim as my invention—

1. In a lamp, in combination, a body having an aperture, a plate hinged to the body and covering the aperture, a bracket for supporting the lamp and being attached to the plate, a socket for an incandescent bulb mounted on the plate, and an electric circuit 80 extending through the bracket and plate to the socket.

2. In combination, a bracket arm having a laterally facing plate provided at its side margins with vertically apertured lugs, a 90 lamp body having an aperture for fitting upon the plate, vertically apertured lugs at each side of the aperture of the body adapted to mate with the lugs of the plate, and pins removably located in the apertures of 95 the coöperating lugs of the body and plate.

3. In combination, a lamp bracket having a pair of parallel tubular hinge ears, a lamp body having a rearward opening and tubular hinge ears flanking the opening and complementary to the hinge ears of the bracket, and hinge pins connecting coöperating 100 hinge ears.

WILLIAM S. HAMM.
